UNITED STATES PATENT OFFICE.

JAMES E. BUCHANAN, OF PAWTUCKET, RHODE ISLAND.

THERMOSTATIC FIRE ALARM.

Application filed October 26, 1925. Serial No. 64,764.

To all whom it may concern:

Be it known that I, JAMES E. BUCHANAN, a citizen of the United States, residing at Pawtucket, in the county of Providence and 5 State of Rhode Island, have invented certain new and useful Improvements in Thermostatic Fire Alarms, of which the following is a specification.

My invention relates to the thermostatic fire 10 alarms and has for its essential objects sensitiveness, certainty of action, and simplicity.

To the above ends primarily my invention consists in such parts and in such combinations of parts as fall within the scope of the 15 appended claim.

In the drawings herewith, which form a part of this specification—

Figure 1 is a front elevation of my novel 20 device, showing a part broken away, and the gong omitted,

Figures 2 and 3, sections of the complete device on lines 2—2 and 3—3 respectively of Figure 1,

Figure 4, an elevation taken from line 25 4—4 of Figure 1, and

Figure 5, a section on line 5—5 of Figure 2.

Like reference characters indicate like 30 parts throughout the views.

My device comprises an oblong upright back 6 with vertical lateral guide shoulders 7 forming a central guideway 8 extending throughout its length. The back is adapted 35 to be attached or suspended to a wall, in this instance by a flat metallic loop 9 attached by a pin 10 to the upper portion of the back. A hook 12 is disposed centrally of the guideway in the front face of the upper part of 40 the back. Below this is a fuse 13 of a metal fusible at a temperature predetermined for the operation of the alarm. Embedded in the upper end of the fuse is a portion of a wire 15 provided with an exposed coiled 45 loop 16 engageable with the hook 12. Embedded in the lower end of the fuse is a second wire 18 with an exposed coiled loop 19 engageable with a hook 20 upon a wire loop 22 passing through a transverse hole 23 in the upper central portion of a flat rectangular weight 25 slidably mounted in the guideway 8 in contact with the shoulders, and provided with a beveled lower extremity 26. In this instance a guard strip 28 is fixed by 50 attaching screws 29 to the shoulders.

Below the weight is a circular base plate

31 fixed to the shoulders by screws 32 and provided with a downwardly directed flange portion 33 resting against the shoulders, the whole forming a cup or housing. A gong 35 60 has an internally threaded centrally disposed projection 36 adapted to engage the threaded outer end of a post or shaft 38 rotatable in a perforation 39 in the base 31 and in a similar perforation 40 in a front plate 41 supported by posts 42 upon the base. The lower end of the post has attached thereto one end of a main spring 44 whose other end is fixed to a rearwardly directed stud or post 46 fixed in the lower 70 portion of the base 31. Fixed in the upper portion the latter is a tubular post or stud 47. Engaging the studs in grooves 48 and 49 respectively is a rear guard plate 50 for the spring and against which the end of 75 the post 38 abuts. Rigid on the post 38 is a ratchet 52 engaged by a pawl 53 pivoted by a pin 54 to a toothed wheel 55 loose on the post. A spring 56 fast to wheel 55 presses the pawl. The member 38 operates 80 as a key shaft when the gong is manually rotated in one direction to tighten the spring, the pawl acting as a check during the winding.

A hammer 58 enclosed by the gong has an 85 arbor stem 60 of flat material provided with a reversely bent end portion 61 pivoted upon a pin 62 fixed in the base and front plates. There are spaced prongs or lips 64 upon the arm portion 61 as shown in Figure 1. 90 The hammer is vibrated against the gong from the shaft 38 through a gear train which includes toothed disk 55 meshing with a pinion or lantern wheel 66 fast to a spur wheel 67 upon a post 68 in the plates. The 95 latter wheel meshes with a second gear 70 fast to a toothed wheel 71 rotatable on a post 72 in the plates and engageable with the lips 64 whereby the hammer stem is vibrated.

The gear train is normally locked or retained against operation by a check device which includes a resilient arm or plate 74 fastened to the upper face of the base plate 31 by the riveted head 75 of the pin 46 105 which extends through a hole 76 in the lower end of the arm. An upturned lug 77 upon the latter has a lateral lip or projection 78 engaging the teeth of the spur wheel and holds the gear train motionless 110 against the force of the spring 44. A pin or plunger 79 slidable in the tubular post 47

projects rearwardly from the post and is provided with a conical or rounded head 80 normally pressed by the arm 74 into contact with the center of the back 6 at a central point in the guideway 8 in the path of the beveled portion 26 of the weight 25. As the outer end of the pin 79 bears against the rear face of the free end of the arm 74, an outward movement of the pin throws the lip 78 out of engagement with the spur wheel 67 and releases the latter. When outward pressure upon the pin is discontinued the arm 74 moves rearwardly and again engages the teeth of the wheel 67.

15 When the temperature adjacent the member 13 reaches or approaches the fusing point the weight 25 withdraws the wire 18 therefrom so that the broad point of its beveled portion descends between the back 6 and the head 80 thus impelling the member 79 forwardly to release the train and operate the gong as described. Until the weight 25 is manually lifted from contact with the head 80 the gong sounds.

25 I claim:—

In a thermostatic fire alarm, a back provided with a vertical guideway, a hook in

the back in the upper portion of the guideway, a fusible member, a wire embedded in the upper portion of the fusible member 30 detachably engaging the hook, a second wire embedded in the lower portion of the fusible member, a weight slidably mounted in the guideway below the fuse detachably supported by the second wire, and provided with a beveled lower end, a transverse base plate fixed to the back below the weight and spaced from the rear of the guideway, a shaft in the plate, a gong on the shaft, a vibratory hammer carried by the plate and 40 adapted to contact with the gong, a gear train operable to actuate the hammer, a resilient plate fastened near one end to the base plate, a projection on the resilient plate normally engaging the gear train, a pin slidably supported in the base plate at right angles to the back projecting into the path of the weight and in contact with the resilient plate whereby the latter will be moved to release the train when the weight descends.

In testimony whereof I have affixed my signature.

JAMES E. BUCHANAN.
